DESIGN FOR A BINOCULAR

Daniel N. Bugel, Rutherford, N. J., assignor to
Columbia Protekosit Co., Inc., Carlstadt,
N. J., a corporation of New Jersey

Application December 16, 1944, Serial No. 116,937

Term of patent 7 years

(Cl. D57—1)

To all whom it may concern:

Be it known that I, Daniel N. Bugel, a citizen of the United States and resident of Rutherford, in the county of Bergen and State of New Jersey, have invented a new, original, and ornamental Design for a Binocular, of which the following is a specification, reference being had to the accompanying drawing, forming a part thereof, and of which Figure 1 is a plan view of a binocu-

lar showing my new design; Fig. 2 is a front end view thereof; Fig. 3 is a sectional view taken on the broken line 3—3 of Fig. 1; and Fig. 4 is a sectional view taken on line 4—4 of Fig. 1.

I claim:

The ornamental design for a binocular, substantially as shown.

DANIEL N. BUGEL.
